UNITED STATES PATENT OFFICE.

CHARLES R. ADAIR AND FRANK A. BANE, OF NARROWS, VIRGINIA.

DELIVERING-CABINET.

1,144,928.

Specification of Letters Patent. Patented June 29, 1915.

Application filed October 8, 1914. Serial No. 864,964.

To all whom it may concern:

Be it known that we, CHARLES R. ADAIR and FRANK A. BANE, citizens of the United States, residing at Narrows, in the county of Giles and State of Virginia, have invented certain new and useful Improvements in Delivering-Cabinets; and we do hereby declare the following to be a full, clear, and exact description of the invention, such as will enable others skilled in the art to which it appertains to make and use the same.

This invention relates to new and useful improvements in delivering cabinets and has for its principal object to provide a device by which the user may easily and quickly determine the amount which should be in the cash drawer.

Another object of the invention is to provide a single delivering cabinet which will prevent more than one package being removed at a time.

A further object of the invention is to provide an adjustable indicating strip whereby the amount which should be in the cash drawer may be readily determined without taking into consideration previous sales.

A still further object of the invention is to provide a novel means for adjusting the indicating tape and holding the same in its adjusted position.

With these and other objects in view as will become more apparent as the description proceeds, the invention consists in certain novel features of construction, combination and arrangement of parts as will be hereinafter more fully described and claimed.

For a complete understanding of our invention, reference is to be had to the following description and accompanying drawings, in which,

Figure 1 front view in elevation of an indicating cabinet constructed in accordance with this invention. Fig. 2 is a vertical sectional view taken through the center of one of the package containing chambers, Fig. 3 is an enlarged detail view in elevation of one of the tape adjusting members, Fig. 4 is an edge view of Fig. 3, and Fig. 5 is a detail fragmentary view illustrating the slot and groove in which the tape runs.

Referring now to the drawings by characters of reference, the numeral 1 designates as an entirety the case, which comprises the vertical side walls 2 which are connected by the rear wall 3. A suitable top wall 4 is

provided and the front is closed by the door, designated generally by the numeral 5. This door comprises a frame 6 in which the glass panel 7 is secured, a suitable lock, the key hole of which is designated by the numeral 9 is provided, and this lock is arranged to secure the door in its closed position. A spindle partition wall 10 is secured between the side walls 2, and this partition wall extends below the bottom of the door frame, as at 11, and is provided with a suitable strip 12 which extends beyond the lateral edges of the partition 10 to form guide ways on which the contents of the case rest. Suitable cleats 13 are provided, and these cleats are arranged so that their upper edges come in direct horizontal alinement with the upper edges of the strip 12 as clearly illustrated in Fig. 1. The rear wall 3 of the case is provided with the longitudinal slot 14 which is formed centrally of the groove 15, which groove is located intermediate the sides of each of the chambers which are formed laterally of partition wall 10. Formed at each end of the slot 14 is the enlarged opening 16 in which the pulleys, which will be more fully hereinafter described are journaled. The rear wall 3 is inset above the rear edges of the side walls 2, and this back wall forms a support for the pulleys hereinbefore mentioned. A suitable cover plate 17 is secured to the rear edges of the walls 2 at their upper end and forms a protecting cover to prevent the operation of the upper roller from being interfered with. A similar plate 18 is secured in a similar manner and is arranged to protect the lower roller as clearly shown in Fig. 2.

Pivotedly secured on the transversely extending bar 19 which is located at the lower forward edge of each of the side walls, is the drawer designated generally by the numeral 20, which drawer comprises the bottom wall 21, front wall 22 and rear wall 23. A suitable cover 24 is secured to the upper edges of the side walls of the drawer 20, and partially extends over the top of the drawer, and this wall is provided at its outer end with the pivoted portion 25 which permits of easy access to the interior of the drawer. A suitable curved false bottom 26 extends from the lower rear corner of the box to the upper front corner and thus allows the user to easily and quickly withdraw change from the interior of the drawer when the same is in its lowered position.

The indicator strip hereinbefore referred to is designated by the numeral 27, and comprises a piece of tape having centered thereon the figures 28 which indicates the amount which will be in the cash drawer. This tape is adjusted by means of the block designated generally by the numeral 29, which block comprises the body 30 having formed thereon the longitudinally extending reduced rib 31 which projects into the slot and forms a guide for the block. A centrally located internally screw threaded aperture is formed within the block and is arranged to receive the threaded stem 32 of the thumb screw 33 which projects through a centrally located aperture formed in the member 34 of the follower, which is designated generally by the numeral 35. This follower 35 comprises the member 34 having formed thereon the horizontally extending bar 36, the lower edge of which is bent angularly as at 37 to engage the uppermost box within the case.

The strip 27 hereinbefore referred to is arranged to run over the rollers or wheels 38 which are journaled on the axle 39 to permit the tape to be easily moved.

It will be apparent from the foregoing, that in use the follower 35 is first moved upwardly to the top of the case and the boxes containing the articles to be sold are then placed in position within the case. The follower is then pressed downwardly until the angular projection 37 engages the uppermost package or article, and the thumb screw 33 is then tightened so that the clamping member 49 will engage the rear wall of the casing and thus hold the case against movement. Upon removing the bottommost package which is designated by the character A, it will be apparent that the box or package which rests thereupon will fall until it engages the strip 12 and cleats 13 which will limit the downward movement thereof, and this operation will cause the member directed in the rear of the uppermost package to be exposed, thus indicating the amount which should be in the cash drawer. After the day's bills have been accounted for, the user may then unlock the door and release the tape to permit the same to be pressed downwardly against the uppermost package so that a new day may be begun and any accounting for the previous amount is thereby unnecessary.

It will be apparent from the foregoing that a particularly simple and efficient device is provided which may be made to easily account for the amount which should be in the cash drawer regardless of the num-

ber of days or periods of time over which the device has been used, and it will be apparent that the book-keeping system will thereby be considerably simplified.

While in the foregoing there has been shown and described the preferred embodiment of this invention, it will be understood that such changes may be made in the combination and arrangement of parts as will fall within the spirit and scope of the appended claims.

What is claimed is:

1. An indicating and delivering cabinet, including a casing, a vertically adjustable indicator tape within the casing, graduations on the tape, and means to prevent the withdrawal of more than the bottom package from the casing when it is in use. 75

2. An indicating and delivering cabinet, including a casing, a vertically adjustable indicator tape within the casing, graduations on the tape, means to lock the tape in adjusted position, and means to prevent the withdrawal of more than the bottom package from the casing when it is in use. 85

3. An indicating and delivering cabinet including a casing, a vertically adjustable indicator tape within the casing, graduations on the tape, a follower on said tape, a thumb screw extending through the follower and tape, a clamp co-operating with the thumb screw and follower to engage the back of the casing and lock the tape against movement, and means to prevent the withdrawal of more than the bottom package from the casing when it is in use. 90

4. An indicating and delivering cabinet including a casing, the back wall of the casing being slotted, a transparent door forming the front wall of the casing, a vertically adjustable indicator tape within the casing and overlying the slot in the rear wall thereof, graduations on the tape, a follower on the tape, a clamping block co-operating with the follower, a thumb screw extending through the follower and into the clamping block, said block and follower being on opposite sides of the back, and cleats secured to the side walls of the casing at a point slightly below the lower end of the door to prevent more than one package from being withdrawn from the cabinet at one time. 100 105 110

In testimony whereof we affix our signatures in presence of two witnesses.

CHARLES R. ADAIR.
FRANK A. BANE.
